UNITED STATES PATENT OFFICE.

WILLIAM E. POINSETT AND JAMES P. POINSETT, OF WILMINGTON, DELAWARE.

LEATHER-SEASONING MACHINE.

1,186,126.

Specification of Letters Patent.

Patented June 6, 1916.

Application filed August 1, 1914. Serial No. 854,469.

To all whom it may concern:

Be it known that we, WILLIAM E. POINSETT and JAMES P. POINSETT, both citizens of the United States, residing at Wilmington, 5 ton, county of New Castle, State of Delaware, have invented a new and useful Leather-Seasoning Machine, of which the following is a specification.

Our invention consists of a novel automatic machine for applying seasoning, oil or other liquids to skins, hides or leather or similar sheet-articles, in which the liquid is applied to the article and thereupon rubbed or brushed into the surface of the skin.

15 It further consists of means for alternately rubbing or brushing the coated skin in opposite directions.

It further consists of means for imparting such alternating motions to the rubbing 20 or brushing elements.

It further consists of other novel features of construction, all as will be hereinafter fully set forth.

The annexed drawings and the following 25 description set forth in detail one mechanical form embodying the invention, such detail construction being but one of various mechanical forms in which the principle of the invention may be used.

30 In said annexed drawings—Figure 1 represents a side elevation of our improved machine. Fig. 2 represents a longitudinal vertical section of the machine. Fig. 3 represents a horizontal section of the machine.

35 Fig. 4 represents an end elevation of the machine. Fig. 5 represents a plan view of the rocking brush-frame. Fig. 6 represents a detail view of the liquid container and the means for applying the liquid. Fig. 7 40 represents an end-view of the swinging frame carrying the rubbing brushes.

Similar numerals of reference indicate corresponding parts in the figures.

Referring to the drawings, the reference 45 numerals 1 indicate side-frames of the machine, and a drive-shaft, 2, having a loose pulley, 3, and a fast pulley, 4, is journaled upon one of said side-frames and can have rotary movement communicated to it by a 50 belt from a suitable source of motion. Said drive-shaft has a bevel-pinion, 5, which meshes with a bevel pinion, 6, upon a shaft, 7, journaled upon the side-frames and having two sprocket-wheels, 8 and 9, one near 55 each end of the shaft. The drive-shaft car-

ries a worm, 10, which meshes with a worm-gear, 11, upon the end of a drum-shaft, 12, longitudinally journaled in the machine-frame. A drum, 13, is secured upon said shaft, being composed of hubs, 14, secured 60 upon the shaft and having radiating spokes, 15, and rims, 16, to which a cylindrical drum-shell, 17, is secured. The rims are formed at registering intervals with peripheral recesses, 18, and the shell is formed 65 with corresponding longitudinal recesses, 19, secured in the recesses of the rims and dividing the circumference of the drum into equal curved tables or bolsters, 20, upon which the skins to be treated are spread. 70 Two arms, 21, are pivoted at their inner ends upon the drum-shaft, outside of the hubs of the end drum-wheels, the hubs, 22, of said arms bearing against the ends of the wheel-hubs, and a shaft, 23, is journaled in 75 the outer ends of said arms, and end-pieces, 24, of a longitudinal frame having side-bars, 25, are pivoted at their middles upon said shaft. Rods, 26, having rollers, 27, journaled in their forked inner ends, 28, to bear 80 against the peripheries of two cams, 29, upon the drum-shaft, are slideable in bearings, 30, pivoted upon the outer sides of the rock-arms, and said rods are adjustably coupled by screw-couplings, 31, to rods, 32, pivotally 85 connected to the end-pieces of the rocking frame to rock said frame as the cams raise and lower the bearing-rollers. The cams have preferably one segmental bulge, 33, to rock the frame, once for each revolution of 90 the cams, and the cams are secured upon sleeves, 34, rotatable upon the drum-shaft and having gears, 35, meshing with idlers, 36, which mesh with gears, 37, upon shafts, 38, journaled in the ends of the machine-frame and parallel with the drum-shaft, which latter gears 37 are connected to pinions, 39, upon said shafts, which pinions mesh with larger gears, 40, upon the drum-shaft. Cam-disks, 41, are secured upon the 100 counter-shaft 38 and have cam-grooves, 42, in their outer faces, in which rollers, 43, upon pitmen, 44, engage and travel. The inner ends of said pitmen have forked heads, 45, which straddle and are slideable 105 upon the countershafts, and the outer ends of the pitmen are pivotally connected to two levers, 46, the lower ends of which are pivoted upon a longitudinal rod, 48, secured to the side-frames of the machine, and to the 110

upper ends of which are pivoted connecting-rods, 49, the inner ends of which are pivoted to the rock-arms 21 carrying the swinging frame.

5 Upright brackets, 50, extend from the side-frames of the machine and a longitudinally grooved or fluted roller, 51, has the ends of its shaft, 52, journaled in hangers, 53, projecting from a bar, 54, parallel with 10 the drum and supported upon the brackets. A pan, 55, is suspended between the upper portions of the hangers and has an upturned edge, 56, which bears against the fluted roller, being drawn against the latter by 15 springs, 57, secured to the hangers and pan. The liquid with which the leather is treated, which in the present instance is the so-called seasoning, is filled into the pan, one side of 20 which is formed by the fluted roller, and when said roller is rotated, it will carry such liquid with it in its grooves.

A brush-roll, 59, is journaled beneath the trough and roller to have its bristles contact with the fluted feed-roller. The fluted 25 roller carries a sprocket-wheel, 60, around which passes a sprocket-chain, 61, passing around a sprocket-wheel, 62, upon the drum-shaft. A sprocket wheel, 63, is revoluble upon the drum-shaft and connected to the 30 sprocket 62, and a sprocket-chain, 64, passes around said sprocket-wheel and the sprocket-wheel 9 upon the shaft 7. The brush-roll has a pinion, 65, which meshes with a pinion, 66, engaging a pinion, 67, upon the shaft of 35 the fluted feed-roller.

Brush-rolls, 66 and 67, are journaled with the ends of their shafts in the end-pieces of the rocking frame, and one brush-shaft, 68, of the brush 66 has a sprocket-wheel, 69, 40 around which passes a chain, 70, which passes around a sprocket-wheel, 71, upon a stub-shaft, 72, in one end-piece of the rocking frame, which sprocket-wheel is connected to a pinion, 73, meshing with a pinion, 74, 45 upon the shaft 23 journaled in the rocking-arms. A sprocket-wheel, 75, is secured upon the other end of said shaft and has a sprocket-chain, 76, passed around it, which chain passes around a sprocket-wheel, 77, 50 revoluble upon the drum-shaft and connected to a sprocket-wheel, 78, also revoluble upon said shaft and having a sprocket-chain, 79, passing around it and around the sprocket-wheel, 80, is secured upon the shaft 55 23 alongside of the sprocket-wheel 75 and has a chain, 81, passing around it and around a sprocket-wheel, 82, upon the shaft of the brush-roll 67.

The longitudinal troughs or recesses 19 of 60 the drum are preferably slightly inclined toward one end of the drum, and a box or receptacle, 83, is supported beneath that end of the drum to receive surplus liquid collecting in said troughs and flowing out at 65 the ends of the same.

A removable sheet-metal plate, 87, is preferably removably placed in each trough of the drum to form a concave removable bottom for the same.

A curved scraper-blade, 88, is pivoted at 70 its ends to bear with its edge against the surface of the drum, and weights, 85, or similar counterbalancing means, upon arms, 86, projecting outward from said blade, yieldingly holds the edge of the latter in contact with 75 the periphery of the drum to scrape waste treating-liquid off from the latter and prevent such waste liquid from contacting with the flesh-sides of the skins and soiling the same.

In practice, the skin, or whatever flat and sheet-like article is to be treated, is placed upon a table or bolster of the drum which rotates in the direction of the arrow in Fig. 1 of the drawings. The skin passes against 85 the seasoning or liquid applying brush-roll, the bristles of which are charged with the liquid by the fluted roller which carries the liquid out of the trough to such bristles, and such liquid is applied to the surface of the 90 skin. The skin travels to the rubbing brush-rolls in the rocking frame which rub the liquid into the skin. The rubbing brushes rotate in opposite directions so that the liquid will be thoroughly rubbed into the 95 skin and the frame being rocked upon the ends of the arms will alternately bring one or the other of such brushes in contact with the skin. As the rocking frame is moved forward and back as the skin travels beneath 100 the brushes, the skin is subjected to the action of the brushes several times while traveling forward, and the rocking frame will be at right angles to the rocking arms when the recesses on the drum pass beneath 105 the same, with the brushes out of contact with the drum, so that the last treated skin can be freely removed and the next succeeding skin pass freely beneath the brush-rolls.

The fluted roller takes up the seasoning 110 liquid in its longitudinal grooves, and the edge of the trough will scrape such liquid off from the roller, excepting the liquid within the grooves, which will be removed by the brush and applied to the leather. 115 The quantity of liquid can be gaged by the size and number of longitudinal grooves in the fluted roller, and the quantity of liquid taken up and transferred to the liquid-applying brush-roll will be even, as it is 120 controlled by the size and number of grooves which will continually take up and contain even quantities of liquid.

The gearing which drives the oscillating 125 and rocking frame and the rubbing brush-rollers in the same is so adjusted that the brush-roller in contact with the skin will rotate to brush toward the end of the skin, and that the skin will be held against the surface of the table on the drum and will 130

not be curled up, as it would be if the rotation of the brush would be from the ends inward. The rotation of the brush-rollers is so that each end of the skin will be 5 brushed outward from the middle and thus be held against the carrying table.

We desire to call special attention to the 10 novel automatic features of our machine, since it will be apparent that the imparting of a simultaneous rotary and oscillatory movement to the brush rolls 66 and 67 simultaneously with the rotation or actuation of the skin carrier or drum 13 is entirely automatic, and is performed in unison 15 with the rotation of said skin carrier 13 without requiring attention on the part of the operator and all treadles or manually operated devices or the like are entirely dispensed with. The feature of actuating 20 said brush rolls in the manner described, automatically at the proper intervals, with respect to the rotation of the skin carrier so that each brush roll at the proper periods acts upon the portions of the skin in the 25 manner described, is one of great importance in this art, in practice, and so far as we are aware, we are the first in the art to construct a machine, wherein said brush rolls have the movements herein described 30 imparted to them simultaneously and automatically, by proper mechanism common to and coacting with the movable or rotatable skin carrier.

So far as we are aware, the actuating 35 mechanism common to the movable or rotatable skin carrier and the brush rolls, which have the simultaneous rotary and oscillatory movements described, is novel, and our claims to these various features should be 40 interpreted with the corresponding scope accorded to inventions of this character.

It will be understood from the foregoing 45 that our machine is entirely automatic in its operation, and the necessity of the employment of foot treadles or manually operated devices to effect the operation of the brush rolls and their adjuncts is entirely avoided by our novel construction.

While we have described our machine as 50 particularly adapted for use as a seasoning or leather finishing machine, it will be apparent that in the broad aspects of our invention, the same is applicable generally to the coating of any desired material other 55 than leather or the like, and that other liquids than seasoning or oil may be employed in conjunction with our machine, for coating the desired articles, without departing from the spirit of our invention.

60 It will now be apparent that we have devised a novel and useful construction of a leather seasoning machine which embodies the features of advantage enumerated as desirable in the statement of the invention 65 and the above description, and while we

have, in the present instance, shown and described a preferred embodiment thereof which will give in practice satisfactory and reliable results, it is to be understood that the same is susceptible of modification in 70 various particulars without departing from the spirit or scope of the invention or sacrificing any of its advantages.

Having thus described our invention, what we claim as new and desire to secure by Letters Patent, is:—

1. In a machine for treating skins, a rotatable drum, a container for the treating liquid, a rotary brush-roll, means for feeding the liquid to said brush-roll, a rubbing brush-roll, and means for reciprocally moving such roll in a path concentric with said drum.

2. In a machine for treating skins, a rotatable drum, a container for the treating liquid, a rotary brush-roll in proximity to the circumference of said drum, means for feeding the liquid to said brush-roll, a frame having means for reciprocatingly moving it in proximity to and in a path concentric with said drum, brush-rolls in said frame and having means for rotating them in opposite directions, and means for rocking such frame to bring either brush in contact with the drum.

3. In a machine for treating skins, a rotatable drum having longitudinal recesses in its circumference forming equal curved tables, and brush-rolls for applying and rubbing in the treating liquid and arranged to 100 impinge upon the circumference of said drum.

4. In a machine for treating skins, a rotatable drum having longitudinal recesses in its circumference forming equal curved tables, means for applying treating liquid to articles upon such tables, and rotary rubbing means having means for reciprocating them upon the articles upon said tables.

5. In a machine for treating skins, a rotatable drum having longitudinal recesses in its circumference forming equal curved tables, means for applying treating liquid to articles upon such tables, means for rubbing such liquid upon the article upon a table, and means for reciprocating such rubbing means forward and back over such article.

6. In a machine for treating skins, a rotatable drum, a frame supported to reciprocate parallel with the circumference of such drum and pivoted to rock upon its support, means for reciprocating such frame, means for rocking said frame, rubbing rollers journaled in said frame and across said drum, and means for rotating such rollers in opposite directions.

7. In a machine for treating skins, a rotatable drum, arms pivoted concentric with said drum, a frame pivoted to rock in the outer ends of said arms, means for rocking

- said arms, rubbing rolls journaled in said frame, means for rotating said rolls in opposite directions, and means for rocking said frame in the outer ends of said arms.
- 5 8. In a machine for treating skins, a rotatable drum, a container for the treating liquid, a rotary brush-roller arranged to receive such liquid and arranged in contact with said drum, means for rotating said roller, a frame supported to reciprocate parallel with the periphery of said drum, brush-rollers journaled in said frame, means for rotating said rollers in opposite directions, means for reciprocating said frame, and means for 10 rocking said frame to alternately bring a brush-roller in contact with the drum.
9. In a machine for treating skins, a rotatable drum, a liquid applying roller contacting with said drum, a plurality of rubbing brush-rollers having means for rotating them, means for reciprocating said rollers in contact with the periphery of such drum, and means for alternately reversing the rotation of said brush-rollers.
- 10 10. In a machine of the character stated, a skin carrier, a plurality of brush-rolls, and automatic means for imparting a simultaneous rotary and oscillatory movement to said brush-rolls.
11. In a machine of the character stated, a skin carrier, a plurality of brush-rolls, means for rotating said brush-rolls in opposite directions, and automatic means for imparting to said brush-rolls oscillatory movement with respect to said skin carrier.
12. In a machine of the character stated, a skin carrier, a plurality of brush-rolls, automatic means for imparting reciprocating movement of one of said elements in its relation to the other, means for imparting rotary motion to said brush-rolls, and automatic means for alternately imparting oscillatory movement to said rolls.
13. In a machine of the character stated, a skin carrier, a plurality of brush-rolls, means for imparting reciprocating movement of one of said elements in its relation to the other, means for imparting rotary motion to said brush-rolls, and automatic means for alternately imparting oscillatory movement to said rolls to bring each one of said brush-rolls toward and from said carrier.
14. In a machine of the character stated, a skin carrier, a plurality of brush-rollers, means for imparting reciprocating movement of one of said elements in its relation to the other, automatic means for alternately imparting oscillatory movement to said rollers to bring each one of the same toward and from said carrier, and means for rotating said brush-rollers in opposite directions.
15. In a machine of the character stated, a skin carrier, a pair of brush-rollers journaled transversely to said carrier, means for rotating said rollers to have the sides facing said carrier travel in diverging directions, and automatic means for alternately moving said rollers toward and from said carrier.
16. In a machine of the character stated, a skin carrier, a plurality of brush-rollers journaled transversely to said carrier, and automatic means for rotating said rollers with the sides facing said carrier traveling in diverging directions.
17. In a machine of the character stated, a skin carrier, a plurality of brush-rollers, means for rotating said brush-rollers in opposite directions, a support for said rollers, means for reciprocating such support, and automatic means for rocking said support to alternately move the rollers in the same toward and from said carrier.
18. In a machine of the character stated, the combination of a rotatable skin carrier, a plurality of brush rollers coacting therewith, and connections intermediate of said skin carrier and brush rolls for automatically imparting a simultaneous rotary and oscillatory movement to said brush rolls, each of the latter being rotated in opposite directions.
19. In a machine of the character stated, a drum having longitudinal recesses in its periphery dividing the same into tables and formed inclined toward one end of said drum, and a receptacle beneath said end to receive liquid from said recesses.
20. In a machine of the character stated, a drum having recesses therein dividing it into tables, and a scraper yieldingly supported to bear against the periphery of said drum.
21. In a machine of the character stated, a skin-carrier, a plurality of brush-rolls, and means for automatically and simultaneously imparting rotary movement to the individual rolls and for imparting automatically oscillatory motion jointly to said rolls relative to said carrier.
22. In a machine of the character stated, a skin-carrier, a plurality of brush-rolls, means for automatically and alternately rotating said brush-rolls in opposite directions, and means for automatically and jointly moving such rolls alternately in opposite directions relative to said carrier.
23. In a machine of the character stated, a skin-carrier, a plurality of brush-rolls, means for automatically imparting reciprocating movement of one of said elements to the other, means for automatically rotating such rolls in opposite directions, and means for automatically and alternately moving such rolls toward and from the carrier.
24. In a machine of the character stated, a skin-carrier, a plurality of brush-rolls, means for imparting reciprocating movement of one of said elements in its relation to the other, means for automatically and alternately moving

- alternately imparting rotary motion to said brush-rolls, and means for automatically and intermittently moving each one of such brush-rolls toward and from said carrier.
- 5 25. In a machine of the character stated, a skin-carrier, a plurality of brush-rolls, means for imparting reciprocating movement to one of said elements in its relation to the other, means for automatically and alternately imparting rotary movement to said rolls in opposite directions, and means for automatically and alternately moving said rolls toward and from the carrier.
- 10 26. In a machine of the character stated, a traveling skin-carrier, a plurality of brush-rolls axially parallel to said carrier, means for oscillating said rolls forward and back over said carrier, means for rotating said rolls in opposite directions, and means for alternately bringing such brush-rolls into and out of contact with said carrier.
- 15 27. In a machine of the character stated, a traveling skin-carrier, a brush-support adjacent said carrier, means for reciprocating one of said elements in relation to the other, brush-rolls journaled in said support, means for rotating said brush-rolls in opposite directions, and automatic means for alternately rocking said support to bring such
- 20 oppositely rotated brush-rolls into and out of contact with the carrier.
- 25 28. In a machine of the character stated, a traveling skin carrier, a brush-support adjacent said carrier and supported to rock with its end alternately toward and from the same, means for reciprocating one of said elements in relation to the other, brush-rolls journaled in the ends of such support to alternately engage the surface of the carrier, means for rotating such rolls in opposite directions, means for rocking said support, and means for automatically actuating all of said elements.
- 30 35 40 45 50 29. In a machine of the character stated, a rotating drum, arms fulcrumed upon the axis of the drum, means for oscillating said arms, a brush support pivoted between the ends of said arms, brush-rolls journaled in said support at opposite sides of its pivotal point, means for rotating said rolls in opposite directions, means for rocking said support, and means connected to said movable elements for simultaneously actuating them.
